LADY'S BATHING GARMENT

Teresina Maria Negri, Paris, France

Application April 29, 1932, Serial No. 608,184
In France March 24, 1932

2 Claims. (Cl. 2-67)

The present invention relates to a bathing garment for ladies' use, which is chiefly characterized by the fact that its upper part is so arranged as to form two pockets, which surround the breasts, and while fitting closely, maintain them in position, without flattening them or exerting any pressure upon them.

The said bathing garment, whose lower part may be made as desired, thus serves to straighten the breasts of the person, and to give an aesthetic appearance to the bust, while allowing an entire freedom for the movements.

According to one form of this garment, the upper part is made up by the following combination, comprising: the top part of a main front piece whose upper edge is cut according to two curves which are convex in the upward direction and are symmetrical with reference to the longitudinal axis of the piece;—two upper pieces which have the symmetrical position on either side of this axis, the lower outline of each piece corresponding to one of the above-mentioned curved lines of the main piece, whilst the upper outline forms at the top a pointed part to which one of the respective shoulder-straps or other holding means is attached;—two lateral and rear elements, which have a triangular or like shape and are attached to the lateral edges of said upper pieces and of the main front piece, and are provided at the rear ends with suitable means by which they can be connected.

The warp yarn of the fabric of the main front piece is preferably parallel with the longitudinal axis of this piece, whilst the warp yarn of the fabric of the two upper elements and of the two lateral elements has practically a horizontal direction.

In the accompanying drawings, which are given solely by way of example:

Fig. 1 is a front view of an improved bathing garment in conformity to the invention, and Fig. 2 is the corresponding side and rear view. Fig. 3 is a front view of a similar costume, in which the two upper front elements consist of open-work, thus allowing the sun's rays to pass through while concealing the skin. Fig. 4 is a front view of another form of garment in which open-work parts are distributed upon the same, and Fig. 5 is a corresponding side and rear view. Fig. 6 is a view in which the assembly of the above-mentioned pieces is shown in the flatwise position and before sewing together, in the case of a garment which is not provided with open-work.

In the form of execution represented in Figs.

1 to 6, the bathing garment, which is made of a suitable fabric of any kind, such as jersey or the like, comprises a main front piece 1, which forms the leg part in the known manner when joined to a back piece 2 (together with a lower connecting piece 3, Fig. 6), the two pieces 1 and 2 being joined at the sides on the lines AB and A'B' (Figs. 2, 5 and 6).

The main front piece 1, in which the warp yarn of the fabric has preferably the lengthwise direction, parallel with the longitudinal axis X—X (Fig. 6), is cut out upon its upper edge in such manner as to form two curves CDE and C'D'E' (Fig. 6). The piece is further cut out at EFE' according to the axis X—X, the two edges EF and E'F being joined as shown in Fig. 1 in order to form a so-called "pinch" from E to F.

To each edge CDE and C'D'E' is sewed a respective upper element 4 and 4', and these two elements, having an outline cd . . . gh and c'd' . . . g'h', are symmetrical with reference to the longitudinal axis X—X of the garment.

The lower edges cde and c'd'e' have their convexed sides turned downward, and thus when they are joined to the respective edges CDE—C'D'E' the piece 1 will form with the pieces 4—4', two pockets adapted to contain the breasts. The curved lines CDE—C'D'E' and cde—c'd'e' have such position that they will extend practically across the nipples of the breasts.

The direction of the warp yarn of the fabric composing the elements 4—4' is preferably parallel with the lower edges cd—c'd', and thus when the garment is fitted in place upon the body, the directions of the warp yarn of the elements 4—4' on the one hand, and of the warp yarn of the piece 1 on the other hand, are practically perpendicular to one another.

The upper edges f'g'h'—fgh of the elements 4—4' which are joined together along the axis X—X by connecting the edges ef and e'f', each forms at g and g' a pointed part which is directed upwardly. To such parts g—g' are attached respective shoulder-straps 6—6'.

To the sides AC and ch of the respective pieces 1 and 4 on the one hand, and A'C' and c'h' of the respective pieces 1 and 4' on the other hand, are attached two elements 5 and 5' IJKL—I'J'K'L' of trapezoidal, triangular or like form, which are provided at the back with suitable means by which they may be attached together, such as a button 8 and button-hole, spring pressure button, clasps etc. This device

may also serve for attaching the shoulder straps 6—6', as shown in Fig. 2. Such straps may also be tied about the neck, as represented in Fig. 5.

The warp yarn of the fabric employed for the 5 elements 5—5' is preferably perpendicular to the sides IJ—I'J', and thus the yarn will have practically the horizontal direction when the garment is worn by the person.

Due to the shape given to the several pieces 1, 10 4, 4', 5, 5', the garment forms two pockets at its upper part, which are adapted to fit closely upon the breasts and to hold them in position, without flattening them. The pinch and the line of junction of the elements 4—4' serve to 15 separate the breasts, which are thus straightened in their form and occupy their normal position. The person thus preserves, or even acquires an aesthetic form, while remaining entirely free in the movements.

20 Obviously, the garment may be made of any suitable fabric having a warp which is more or less close, and the garment may also comprise open work parts which allow the sun's rays to pass through while concealing the forms of the 25 body and the skin.

Fig. 3 shows by way of example a bathing garment in which the upper elements 4 and 4' consist of open work portions and are connected together by a small piece of plain fabric 9.

30 In the arrangement shown in Figs. 4 and 5, the garment comprises open work parts which are distributed upon the whole of the garment.

Obviously, the said invention is not limited to the forms of execution herein described and 35 represented, which are given solely by way of example.

Having now described my invention, what I 40 claim as new and desire to secure by Letters Patent is:

40: 1. A lady's bathing garment comprising a main front piece, the upper edges of which form two curves having their convexity turned up-

wards and disposed symmetrically with respect to the longitudinal axis of said main piece, two upper elements disposed symmetrically on both sides of the longitudinal axis of said main piece, the lower edge of each of said upper elements forming a curve having its convexity turned downwards and assembled to the convex edge of the corresponding portion of said main piece, holding means attached to the upper edge of said upper elements, a rear piece assembled with the lower portion of said main front piece, two rear and lateral flaps, fastened to the lateral edges of said upper elements and to the main front piece above said rear piece and means at the rear ends of said rear and lateral flaps for detachably connecting the same.

2. A lady's bathing garment comprising a main front piece, the upper edges of which form two curves having their convexity turned upwards and disposed symmetrically with respect to the longitudinal axis of said main piece, two upper elements disposed symmetrically on both sides of the longitudinal axis of said main piece, the lower edge of each of said upper elements forming a curve having its convexity turned downwards and assembled to the convex edge of the corresponding portion of said main piece, holding means attached to the upper edge of said upper elements, a rear piece assembled with the lower portion of said main front piece, two rear and lateral flaps, fastened to the lateral edges of said upper elements and to the main front piece above said rear piece and means at the rear ends of said rear and lateral flaps for detachably connecting the same, the warp threads of said main front piece being substantially parallel with the longitudinal axis of said main piece, whereas the warp threads of said upper elements and lateral flaps are substantially perpendicular to said longitudinal axis.
